GARMENT RACK OR ANALOGOUS ARTICLE

Irving Goldbert, Garwood, N. J.

Application April 27, 1954, Serial No. 30,208

Term of patent 3½ years

(Cl. D80—8)

FIG. 1

FIG. 2

To all whom it may concern:

Be it known that I, Irving Goldbert, a citizen of the United States, residing in the town of Garwood, county of Union, and State of New Jersey, have invented a new, original, and ornamental Design for a Garment Rack or Analogous Article, of which the following is a specification, reference being had to the accompanying drawing, forming a part hereof.

In the drawing,

Fig. 1 is a top plan view of a garment rack or analogous article showing my new design;

Fig. 2 is a front elevational view;

Fig. 3 is a side view thereof.

I claim:

The ornamental design for a garment rack or analogous article, substantially as shown.
